UNITED STATES PATENT OFFICE.

WALENTY JEZUIT, OF FISHERVILLE, MASSACHUSETTS.

DESIGN FOR A BRUSH.

SPECIFICATION forming part of Design No. 27,658, dated September 21, 1897.

Application filed August 11, 1897. Serial No. 647,929. Term of patent 7 years.

To all whom it may concern:

Be it known that I, WALENTY JEZUIT, a citizen of the United States, residing at Fisherville, in the county of Worcester and State 5 of Massachusetts, have invented a new and useful Design for Brushes, of which the following is a specification.

My design for brushes is illustrated in the accompanying drawing, which shows a perspective view of a bicycle-cleaning brush embodying my design.

My design for brushes is characterized by a base or body portion 10, having a curved end 11, a bristle-section 12, which extends 15 around said curved portion 11, and a smaller bristle-section 13, the bristle-sections 12 and 13 being separated by a finger-space 14.

Brushes embodying my design can be conveniently carried in the tool-bag of a bicycle, one especial object of my design being to provide a brush designed so that it will take up little room. 20

Having thus fully described my design, what I claim as new, and desire to secure by Letters Patent of the United States, is— 25

The design for brushes, substantially as herein shown and described.

In testimony whereof I have hereunto set my hand in the presence of two subscribing witnesses.

WALENTY JEZUIT.
